CLAIM

The ornamental design for pet glasses, as shown and described.

DESCRIPTION

FIG. 1 is a bottom, front, left perspective view of pet glasses showing my new design;

FIG. 2 is a top, rear, right perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged perspective view of detail “9”, identified in FIG. 2.

The dash-dot-dash broken lines in FIGS. 2 and 9 depict the bounds of the detail views and form no part of the claimed design.

1 Claim, 9 Drawing Sheets(56)
